UNITED STATES PATENT OFFICE

2,468,518

TRUMPET

Otto W. Schlums, Whitinsville, Mass., assignor
to Whitin Machine Works, Whitinsville, Mass.,
a corporation of Massachusetts

Application January 5, 1946, Serial No. 639,386

7 Claims. (Cl. 19—157)

1

This invention relates to trumpets used for condensing and guiding the slivers in textile drafting or drawing machines, such as cards, combers and drawing frames. Such trumpets are commonly mounted on stop motion levers, which are normally held down by the pull of the sliver but which rise and activate the stop motion on breakage of an associated sliver.

It is desirable to condense and guide each sliver to a point as close as practicable to the calender rolls. With the usual trumpets, however, this distance must be nicely adjusted to the length of the fibre, and even then fibres from a bunch caught in a trumpet may extend into the bite of the rolls and exert enough pull to hold the trumpet lever down and prevent the stop motion from operating, even after the feed of the sliver has been interrupted.

It is the general object of my invention to provide an improved trumpet for the purposes above set forth, so constructed that the sliver is guided close to the calender rolls but that at the same time the trumpet lever is free to activate the stop motion on the lodging of a bunch in the trumpet.

A further object of my invention is to provide a trumpet having a partially relieved guiding portion below the usual condensing portion, and in which relieved portion the sliver will be broken on the lodging of a bunch in the trumpet. I also provide a construction in which twin trumpets coact to produce an analogous result.

My invention further relates to arrangements and combinations of parts which will be hereinafter described and more particularly pointed out in the appended claims.

Preferred forms of the invention are shown in the drawings, in which

Fig. 1 is a sectional side elevation of portions of a drawing frame with my improved trumpet operatively mounted therein;

Fig. 2 is an enlarged side elevation of the trumpet;

Fig. 3 is a front elevation, looking in the direction of the arrow 3 in Fig. 2;

Fig. 4 is a sectional plan view, taken along the line 4—4 in Fig. 3;

Fig. 5 is a front elevation, partly in section, showing twin trumpets in operative relation; and

Fig. 6 is a longitudinal sectional view, taken along the line 6—6 in Fig. 5.

Referring to Fig. 1, I have shown portions of a drawing frame for a sliver S and including a plurality of pairs of drawing rolls 10 mounted on a fixed frame 11, a pair of calender or de-

2

livery rolls 12 similarly mounted, a coiling head 14 continuously rotated by any usual driving mechanism, and a can 15 in which the drafted sliver S' is coiled.

5 All of the parts thus far described are of the usual commercial construction, as is also the trumpet lever 20 on which is mounted my improved trumpet T. The lever 20 controls any usual stop motion and is so constructed and mounted that it is held in the position shown in Fig. 1 by the normal pull of the sliver S' passing therethrough. On breakage of the sliver, however, the trumpet T rises and the opposite end of the lever 20 drops to complete an electric circuit or to otherwise activate a stopping mechanism.

10 My improved trumpet T is shown in detail in Figs. 2, 3 and 4 and comprises a head 30, a cylindrical middle portion 31 and a tapered lowered end portion 32. A conical depression 33 in the head 30 guides the drafted sliver S' to a relatively restricted passage 34 in which the sliver S' is condensed or compressed to round and relatively compact form.

15 25 Below the passage 34, I provide a passage 35 relieved to a somewhat increased diameter, and I also cut away one side of the cylindrical portion 31 for a substantial distance as indicated at 36. I also slab off the lower end portion of the trumpet as shown at 37 (Fig. 4) and provide a slot 38 in this portion 37.

20 30 The levers 20 are so positioned that the lower end portions 32 of the trumpets T extend closely adjacent the calender rolls 12 as shown in Fig. 1, this having the advantage that the sliver is presented to the rolls in circular section, rather than in the flat or ribbon-like form which it might otherwise assume. At the same time, the restricted passage 34 is so far removed from the 35 calender rolls 12 that the sliver will readily break in the relieved passage 35 if a bunch is caught in the conical depression 33. Failure of the stop motion to operate, due to fibres caught between the calender rolls, is thus effectually avoided.

35 40 The cut-away portion 36 and the slot 38 are provided to facilitate threading of the trumpet, and the end of each trumpet lever 20 may be recessed for the same purpose, as shown at 40 in Fig. 1.

45 50 In Figs. 5 and 6 I have shown my invention adapted to twin trumpets, which may be used, for instance, in a construction as shown in Bantfield Patent No. 2,301,677, issued November 10, 1942. In such a construction, the trumpets T'

are mounted in trumpet levers 50 and 51 and are so disposed that their condensing passages 52 converge to a common center at the bite of calender rolls 53, one only of which is shown in Fig. 5.

The trumpets T' are a modification of the trumpet T shown in Figs. 2 to 5, and each trumpet comprises a head portion 60 having a tapered or slightly conical extension 61 through which a condensing passage 52 extends.

A guide-plate 63 has a sleeve-like portion 64 partially embracing the extension 61 and permanently secured thereon, as by welding or soldering. The lower part of the guide-plate is formed with a concave or dished inner surface 65 and with converging lower edge portions 66.

The trumpets T' of an associated pair are disposed at opposite angles, as shown in Fig. 5, and with the guide-plates 63 adjacently disposed to form a converging passage. The lower end portions 66 are close enough together to compress and guide the associated slivers to the bite of the calender rolls, while at the same time the relieved passage formed by the guide-plates 63 below the condensing passages 52 allows the fibres to be drawn downward and the sliver to be broken, in the event of a bunch lodging in the conical entrance recess 68 of either of the trumpets T'.

With both forms of my invention, threading is facilitated by having the lower guide passages cut away or open at the side. In threading the single trumpets T shown in Figs. 2 to 4, it is sufficient to draw the end of the sliver through the cut-away portion 36 and then drop the end of the sliver between the calender rolls 12, whereupon the sliver will be automatically drawn through the slot 37 and into the lower end of the relieved passage 35.

My invention is particularly useful when drafting fibres of more than normal length, as resetting of the trumpets is not necessary.

Having thus described my invention and the advantages thereof, I do not wish to be limited to the details herein disclosed, otherwise than as set forth in the claims, but what I claim is:

1. In a fibre drafting mechanism having calender rolls, twin trumpets set at oppositely inclined angles and having a common delivery point, said trumpets delivering sliver direct to said calender rolls and each having a restricted condensing passage and having a delivery passage extending entirely through the exit end of said trumpet and of substantially greater cross section throughout its length than said condensing passage and through which the sliver is delivered relatively freely direct to said calender rolls at said common delivery point.

2. In a fibre drafting mechanism having calender rolls, twin trumpets set at oppositely inclined angles and having a common delivery point, said trumpets delivering sliver direct to said calender rolls and each having a restricted condensing passage and having a concave open guide-plate providing a relatively open lower

60
65

passage through which the sliver is drawn relatively freely and is delivered direct to said calender rolls at said common delivery point.

3. A trumpet comprising a unitary body including a head portion and a shank portion extending therefrom, a conical entrance passage in said head portion, an axially disposed cylindrical delivery passage in said shank portion and an axially disposed restricted cylindrical passage connecting said entrance and delivery passages, said restricted passage being of less diameter than said delivery passage.

4. The device as defined in claim 3, wherein said shank portion is formed with a lateral opening communicating with said delivery passage.

5. In a fibre-drafting mechanism having calender rolls and a trumpet delivering sliver direct to said calender rolls, that improvement which comprises providing said trumpet with an entrance portion having a constricted condensing passage and having a delivery passage of substantial length and of substantially increased cross section and effective to guide the condensed sliver under reduced compression and relatively freely entirely through said delivery passage to the exit end of said trumpet and to the point of delivery of said fibre by said trumpet, and the compression of the fibre being reduced throughout said delivery passage both axially and transversely of said passage.

6. In a fibre-drafting mechanism having calender rolls and a trumpet delivering sliver direct to said calender rolls, that improvement which comprises providing said trumpet with an entrance portion having a restricted condensing passage and with a delivery portion having a relatively long delivery passage of substantially greater dimensions on all diameters and throughout its length and through which the less condensed sliver may pass relatively free direct to the calender rolls.

7. The combination in a fibre-drafting mechanism as set forth in claim 5; in which the delivery passage is cut away on one side at its entrance part to facilitate threading of said trumpet.
